NO. 11,251

JUNE 17, 1879

UNITED STATES PATENT OFFICE

HENRY R. FRISBIE, OF BRIDGEPORT, ASSIGNOR TO E. N. WELCH MANUFACTURING COMPANY, OF FORESTVILLE, CONNECTICUT.

DESIGN FOR CLOCK-CASE.

Specification forming part of Design No. **11,251**, dated June 17, 1879; application filed May 26, 1879.
[Term of patent 7 years.]

To all whom it may concern:

Be it known that I, HENRY R. FRISBIE, of Bridgeport, in the county of Fairfield and State of Connecticut, have originated and produced a new Design for a Clock-Case Front, of which the following is a full, clear, and exact description, reference being had to the accompanying photographic illustration, making part of this specification.

The general design for the front is a representation of a banner; and I term said design the "La Bannière."

A designates the body of the front, the same being square at the top, with vertical sides. The bottom of the body A is formed in curved and straight lines, the middle portion being horizontal and standing on the standard B. Surrounding the body is a central upright in the form of a Latin cross, and extending from the corners of the case, both at the top and bottom, there is a horizontal member with a cross at the end. The horizontal bars at the top and bottom also form, in

connection with the upright at the top and bottom, other crosses, as shown.

A member representing a cord extends from the front of the upright to the upper corners of the body, and thence downward on the border thereof, and terminates in the representation of a tassel. Ornamental figures are placed on the four corners of the front and at other parts, as shown.

I claim as my invention—

1. The design for a clock-case front, which consists, essentially, of the representation of a banner, substantially as shown and described.

2. The design for a clock-case front, consisting, essentially, of the body A and standard B, ornamented by the member which represents a cord and tassel, and also ornamented by the several crosses, substantially as shown and described.

HENRY R. FRISBIE.
